UNITED STATES PATENT OFFICE

ROGER C. BENNETT, OF SEMINOLE, OKLAHOMA, ASSIGNOR OF ONE-HALF TO FRANCIS T. PATTERSON, OF SEMINOLE, OKLAHOMA

COMPRESSED-AIR WELL PUMP

Application filed April 21, 1928. Serial No. 271,846.

This invention relates to pumping mechanisms used principally in withdrawing oil from oil wells, the mechanism being of that character wherein there is a displacement space or area having an inlet and an outlet and wherein fluid pressure from a constant source is intermittently admitted to the displacement space to intermittently cause a displacement of the liquid therein and its 10 discharge therefrom.

The general object of the present invention is to provide a mechanism of this character so formed as to prevent back pressure being exerted upon the oil sand when 15 the motive fluid or fluid pressure is discharged into the displacement area.

A further object is to provide means for directing the fluid under pressure against the valve, which valve acts to prevent the 20 fluid under pressure exerting any pressure upon the sands so as to thus keep this valve cleaned off.

A still further object is to provide a very simple but effective mechanism for this purpose having few and very simple parts so 25 that there will be the least possible chance of this mechanism getting out of order.

Another object is to provide a construction of this kind having a valve preventing the 30 fluid pressure from exerting pressure upon the sands, and provide a piston for the valve operable under fluid pressure, the piston acting first to close the valve and then acting as a valve itself to open the by-pass, permitting 35 fluid pressure to pass down around the piston and be discharged into the displacement area.

Other objects will appear in the course of the following description.

40 My invention is illustrated in the accompanying drawing, wherein:—

Figure 1 is a longitudinal sectional view of the casing of an oil well, a motive fluid tube, and my improved regulating valve, the 45 valve being shown in its open position;

Figure 2 is a like view to Figure 1 but showing the valve in its closed position and the piston depressed.

50 Referring to this drawing, 10 designates a well casing and 11 an interior tubing formed

of sections connected by collars 12. This tubing at one point in its length is provided with openings 13, these being located below a packer 14 and the packer being of any suitable character and extending between the 55 tubing 11 and the casing wall 10.

The tube 11 adjacent one end is provided with an annular piston stop 14 and below this with an exterior sleeve 16, apertures 17 extending from the interior of the tube 11 into the upper portion of said sleeve and apertures 18 connecting between the interior of the tube 11 and the interior of the sleeve. 60

Disposed a distance below the sleeve is a valve seat 19 and just above this valve seat the tube 11 is apertured, as at 20. Disposed within the tube 11 between the sleeve 16 and the valve seat are the spiders 21 and 22. Disposed within the tube 11 adjacent the piston stop 14 is a piston 23, the upper end 70 of which is beveled so as to seat against the stop 14. This piston has a tubular stem 24 which extends down through the spiders 21 and 22. Extending downward through the piston 23 and through its tubular stem 75 is a valve stem 25 having a nut 26 at its upper end bearing against the upper end of the piston and at its lower end provided with a conical valve 27, this valve coacting with the seat 19 and seating thereagainst 80 when the valve is lowered.

Disposed to surround the tubular stem of the piston and disposed between the under face of the piston 23 and the spider 21 is a coiled compression spring 28 which urges the piston upward and thus urges the valve upward, the piston bearing against the nut 26 under these circumstances. Surrounding the lower end of the valve stem 25 is a coiled compression spring 29 which bears at one 85 end against the valve and at the other end against a flange or head 30 formed upon the lower end of the tubular piston stem. Thus any downward movement of the piston stem will first act to compress the spring 29 and 90 when the spring 29 has been compressed to a proper degree the valve will move with the piston.

In the operation of the mechanism, the upper end of the tube 11 is to be connected to 100

any suitable source of constant fluid pressure. This may be, for instance, gas or air under pressure but preferably will be compressed air. The piston 23, when it is raised, closes the ports or perforations 17 so that the fluid pressure can only bear against the upper contracted end of the piston. When the air or gas is forced down the tube 11 under sufficient pressure, it will force the plunger 23 down against the action of the spring 28. The downward movement of the tubular piston stem 24 will cause the compression or spring 29, which is of such strength that the valve 27 will move down immediately that the piston moves downward and the valve will seat against the seat 19, thus cutting off all communication between the upper end of the tube 11 and the lower end thereof.

20. A further downward movement of the piston under the pressure of the air will open the ports 17, as shown in Figure 2, and the compressed air or other motive fluid will pass out through the ports 17, downward 25 around the by-pass sleeve 16, through the ports 18 into the tube 11 below the piston, downward through the spiders 21 and 22, and out through the ports 20, the valve 27 being closed and preventing any further downward movement of the motive fluid. Motive fluid will thus pass into the displacement area A, which is previously filled with oil, and will rise or rush upward, carrying with it the oil in a well known manner.

35. As soon as the pressure has been reduced beyond a certain point and before the oil has been pumped out and pressure reduced, the spring 28 will cause the piston valve to move rearward, closing the port 17, and eventually the piston valve strikes the nut 26 or stop, lifting the valve stem and the valve from the position shown in Figure 2 to the position shown in Figure 1. Oil will then flow upward into the lower portion of the pipe 11 by means of the ports 13 and flow through the seat 19 and apertures 20 into the displacement space A. When the displacement space has been filled the operation is repeated.

It will be noted that in my construction 50 the piston first acts to close the valve and then continues to travel downward so as to open the by-pass and permit the passage of motive fluid down the tube 11 and into the displacement area, and attention is directed to the fact that the ports 20 are located so close to the valve 27 that the motive fluid, moving down swiftly under pressure cleanses the valve of dirt and foreign matter so as to keep the valve in proper 55 condition to seat at all times. When valve 27 is closed, the pressure on the motive fluid cannot be transmitted to the oil sands and this pressure must be entirely utilized in lifting the oil in the displacement area.

60 65 Of course, when the valve 27 is opened by

an upward movement of the piston, air is cut off and all the air that may be within the displacement area is moved upward, carrying with it the oil, so that there is no back pressure at any time upon the oil sands.

70 I claim:

1. In a pump adapted to be associated with a displacement zone having a liquid inlet and liquid outlet a tubular member having a valve seat and having an inlet below the valve seat and an outlet above the valve seat, the outlet discharging into said displacement zone, a valve engageable with said seat, a piston mounted within the tubular member above the valve, is a stem extending from the valve and sliding through said piston and having a stop on its outer end beyond the piston, a spring urging the piston to a raised position and the valve from its seat, a yieldable connection between the piston and the valve permitting the piston to move after the valve has seated to cause the inward movement of the piston to shift the valve to a closed position, and a by-pass, opening at its upper and lower ends into said tube, the piston normally closing the upper end of the by-pass when the valve is raised but the piston, when depressed and the valve seated, acting to open the upper end of the by-pass whereby fluid in the tube may pass around the by-pass and into the tube below the piston.

2. In a pump adapted for association with a displacement area a tube having a valve seat, inlet apertures in the tube below the valve seat, liquid outlet apertures in the tube above the valve seat into the displacement area, a valve coacting with said seat, a piston disposed above the valve, a by-pass surrounding the tube and opening at its upper and lower ends thereinto, the piston when in a raised position closing the upper opening of the by-pass, means operated by a downward movement of the piston under the action of pressure fluid initially causing the closing of the valve, the piston having further movement independently of the valve after the latter has closed acting to pass the upper end of the by-pass to thus permit pressure fluid to pass through said by-pass into the tube below the piston and then pass downward and outward into the displacement zone, and means acting when the pressure of motive fluid on the piston is relieved causing the initial return of the piston to a position closing the upper end of the by-pass and causing the opening of the valve.

3. The combination with a well casing, of means for lifting liquid upward in the well casing comprising a tube disposed within the well casing and having a liquid inlet, a packing engaging the well casing and tube above the inlet, the tube above the packing being formed with a valve seat, and with ports immediately above the seat opening into the area between the tube and casing, a valve co-

acting with this seat, a piston disposed above the valve, a by-pass sleeve opening at its upper and lower ends into said tube, a seat for the piston disposed above the by-pass and stopping the piston when it has closed the upper by-pass opening, a spring urging said piston against said stop, the valve having a stem extending through and sliding in the piston and formed with a stop at its upper end, a spring surrounding the valve stem, the piston having a stem loosely surrounding the valve stem and bearing against said last named spring.

4. The combination with a well casing, of 15 a centrally disposed tube, packing between the tube and the valve casing, the tube below the packing having liquid inlet apertures and above the packing having a valve seat, ports immediately above the valve seat opening 20 into the space between the tube and the well casing and valve, a valve coacting with said seat and having an upwardly extending stem having a stop at its upper end, a piston slideable on the upper end of the stem, a stop 25 against which the piston normally bears, the piston having a tubular stem through which the valve stem loosely passes, a spring surrounding the valve stem and bearing operatively at one end against the valve and at the 30 other end bearing against said tubular piston stem, a compression spring disposed to surround the tubular stem operatively supported at one end upon the tubular member and at the other end bearing against the piston 35 and urging the piston upward against the stop, and a by-pass sleeve disposed around the tubular member and opening at its upper and lower ends into the tubular member, the upper end of the by-pass being normally 40 closed by the piston.

5. In a pumping apparatus operated by the displacement of liquid by fluid under pressure, a casing having an outlet, a central pressure fluid conducting tube, packing disposed between the casing and the tube, the space above the packing constituting a displacement space, the tube having liquid inlet ports below the packing, and a valve seat above the packing, a valve adapted to rest 50 on said seat, means normally preventing the passage of pressure fluid through the ports to the displacement space and holding the valve raised but acting upon an increase in fluid pressure to close the valve and after 55 the valve has closed open communication between the upper portion of the tube and said ports to permit the passage of fluid pressure to the displacement space and upon a decrease in fluid pressure acting to first close said communication and then open the valve to permit 60 passage of liquid to the displacement space.

In testimony whereof I hereunto affix my signature.
